BY *A. S. Allebach*
ATTORNEY

UNITED STATES PATENT OFFICE

AUGUST S. ALLEBACH, OF NORTH WALES, PENNSYLVANIA

ABDOMINAL SUPPORTER

Application filed March 21, 1930. Serial No. 437,898.

My invention has for an object to provide an abdominal supporter so constructed as to distribute the weight of an enlarged abdomen over the entire spinal column.

5 Further, it is an object to provide such a supporter as will support the spine in such a manner as to carry the excess weight of an enlarged abdomen.

Further, it is an object to provide a supporter which prevents abdominal curvature of the spine.

A further object is to provide a supporter of such design and construction that it will relieve the sacro-iliac articulation of undue strain and to prevent dislodgment of same.

Again it is an object to provide a supporter which will prevent an unnatural depression of the thoracic wall in the epi-gastric region and the resulting gastric disturbances and 20 displacements of organs in that region.

Further, it is an object to provide a supporter that will insure a natural erect posture of the body, normal deep breathing, natural functioning of all the organs and unhampered development of the fetus.

Other objects will in part be obvious and in part be pointed out hereinafter.

To the attainment of the aforesaid objects and ends, the invention still further resides 30 in the novel details of construction, combination and arrangement of parts, all of which will be first fully described in the following detailed description, then be particularly pointed out in the appended claims, reference 35 being had to the accompanying drawings, in which:—

Figure 1 is a diagrammatic side view of the human body illustrating the application of my invention.

40 Figure 2 is a side elevation of the human body with the supporter in position properly fitted.

Figure 3 is a rear view of the same.

45 Figure 4 is a perspective view of the supporter.

In the drawings, in which like numerals and letters of reference indicate like parts in all of the figures, A is the supporter proper which is made of suitable material, elastic or 50 non-elastic, shaped to encase a pendulous ab-

domen and fitted to allow unhampered development of the fetus. The lower border (a) reaches to the os-pubis following the groins sideways and upwards, as at (a'), to and into the inguinal region, as at (a''), then upward over part of the right and left anterior lumbar region, as at (a''') to the top border, being there slightly depressed, as at (a''') and passing about two inches below the infracostal line, thus covering part of the 55 umbilical, part of the right and left anterior lumbar region and all of the pubic and right and left inguinal region.

B is a band made of either elastic or non-elastic material equipped with a suitable 60 buckle or slide (b) for adjustment. It is fastened to the supporter proper A on its lower border at the inguinal region, encircling the innominate horizontally at a point just below the anterior superior spines of the ilia and 65 passing directly over the sacro-iliac articulation. 70

The function of the band B is: first, to hold the lower portion of the supporter proper A firm against the abdomen; second, to protect 75 the sacro-iliac articulation; third, to support the base of the spinal column at that point (see arrow 5 in Figure 1).

C represents a separable connector for attaching the straps D and E to the supporter 80 proper. It consists of a part (c'), fastened to the supporter proper A, and a second part (c'') fastened jointly to the ends of the straps or bands D and E. The two parts (c') and (c'') are separably joined by a hook and eye 85 or ring arrangement for ease in taking off and putting on the supporter which, when once adjusted, can readily be taken off and put on without further adjustment at each time.

D is a band or strap made of suitable material, elastic or non-elastic, and is equipped with a buckle or slide (d) for adjusting. The band D rises from its point of attachment (c'') in a vertical line to the shoulder, then over the shoulder downward diagonally at 95 the back, as at (d'), to the median line where it passes through a slide (d''), (for adjusting) to a point at the fourth dorsal (see arrow 2, Fig. 1), and from thence vertically downward as at (d'''), to the sacrum (see arrow 5, 100

Fig. 1) under band or strap B and back upward again, as at (d⁴), over the median line to the adjustable slide (d²) at point of the fourth dorsal, then diagonally over the opposite shoulder, as at (d⁵) and then vertically downward to the fastening attachment C on the other side of the supporter proper A.

E is a band or strap of suitable material, elastic or non-elastic, and is equipped with

- 10 two buckles or slides (e) for adjustment. The band E runs horizontally from its one place of attachment C, crosses the median line at the tenth dorsal (see arrow 3, Fig. 1) to the other side of the attachment at C.
- 15 F represents an octagon shaped pad made of suitable soft material and it is fastened to the bands E and D at a point in the median line at the tenth dorsal.

In the use of my invention, the band D 20 bears the weight over the shoulder and down the back intercepted by the band E at the junction of the bands B and D and produces a forward pressure against the pad F at the tenth dorsal (see arrow 3, Fig. 1), band B 25 being connected to band D at pad F. The spinal column is braced from pad F upwardly, thus preventing curvature of the spine in that region (see arrow 1, Fig. 1).

This same upright posture produced 30 through pressure against pad F prevents the depression of the thoracic wall in the epigastric region. The concerted pull of the bands D and E on the supporter proper a produces an upward pressure and backward 35 pressure, relieving the strain in the lumbar region and reducing abnormal curvature thereof (see arrow 4, Fig. 1) to normal straight position (see straight line of back in Fig. 2).

40 The band B holding the lower border of the supporter proper A against the abdomen, the resultant counter pressure is placed against the sacrum, thereby securing the base of the spine firmly (arrow 5, Fig. 1) 45 thus completing a novel device for supporting an abdomen and supporting the spine in a new and useful manner.

From the foregoing description, taken in connection with the accompanying drawings, 50 it is thought the construction, operation and advantages of my invention will be clear to those skilled in the art to which it relates.

What I claim is:

- 55 1. An abdominal supporter comprising a supporter proper shaped to encase a pendulous abdomen and having a border reaching from the os-pubis, following the groins, sideways and upwards to and into the inguinal 60 region, then upwardly over part of the right and left anterior lumbar region, then curving forward to the top of the border, and means to sustain said supporter proper on the body, said means including a band secured to the 65 lower border of said supporter proper at the

inguinal region and encircling the innominate horizontally at a point adjacent the anterior superior spines of the ilia and passing over the sacro-iliac articulation, and a band connected at its ends to said supporter proper at the upper sides thereof and passing over the shoulders downward and along the median line and looped around said first mentioned band. 70

2. An abdominal supporter comprising a 75 supporter proper shaped to encase a pendulous abdomen and having a border reaching from the os-pubis, following the groins, sideways and upwards to and into the inguinal region, then upwardly over part of the right and left anterior lumbar region, then curving forward to the top of the border, means to sustain said supporter proper on the body, 80 said means including a band secured to the lower border of said supporter proper at the 85 inguinal region and encircling the innominate horizontally at a point adjacent the anterior superior spines of the ilia and passing over the sacro-iliac articulation, and a band connected at its ends to said supporter proper at the upper sides thereof and passing over the shoulders downward and along the median line and looped around said first mentioned band, and a third band connected at its 90 ends to said second band adjacent its connection to said supporter proper and running horizontally from its place of attachment and crossing the median line at about the tenth dorsal. 95

3. An abdominal supporter comprising a 100 supporter proper shaped to encase a pendulous abdomen and having a border reaching from the os-pubis, following the groins, sideways and upwards to and into the inguinal region, then upwardly over part of the right and left anterior lumbar region, then curving forward to the top of the border, means to sustain said supporter proper on the body, 105 said means including a band secured to the lower border of said supporter proper at the 110 inguinal region and encircling the innominate horizontally at a point adjacent the anterior superior spines of the ilia and passing over the sacro-iliac articulation, and a band connected at its ends to said supporter proper at the upper sides thereof and passing over the shoulders downward and along the median line and looped around said first mentioned band, and a third band connected at its 115 ends to said second band adjacent its connection to said supporter proper and running horizontally from its place of attachment and crossing the median line at about the tenth dorsal, and a pad of suitable soft material 120 secured to said second and third bands where they cross at the median line. 125

4. An abdominal supporter comprising a 130 supporter proper shaped to encase a pendulous abdomen and having a border reaching from the os-pubis, following the groins, side-

ways and upwards to and into the inguinal region, then upwardly over part of the right and left anterior lumbar region, then curving forward to the top of the border, means to 5 sustain said supporter proper on the body, said means including a band secured to the lower border of said supporter proper at the inguinal region and encircling the innominate horizontally at a point adjacent the anterior 10 superior spines of the ilia and passing over the sacro-iliac articulation, a band connected at its ends to said supporter proper at the upper sides thereof and passing over the shoulders downward and along the median 15 line and looped around said first mentioned band, a third band connected at its ends to said second band adjacent its connection to said supporter proper and running horizontally from its place of attachment and crossing 20 the median line at about the tenth dorsal, and a pad of suitable soft material secured to said second and third bands where they cross at the median line, and means to adjust the lengths of said bands in fitting the supporter to the wearer.

5. An abdominal support comprising a supporter proper shaped to encase a pendulous abdomen, and a harness for carrying said supporter proper, said harness including 30 means to distribute the weight of the abdomen over the entire spinal column and supporting the spinal column to carry the additional weight of the abdomen.

6. An abdominal support comprising a 35 supporter proper shaped to encase a pendulous abdomen, and a harness for carrying said supporter proper, said harness including a band secured to the lower border of said supporter proper at the inguinal region and encircling the innominate horizontally at a point adjacent the anterior superior spines of the ilia and passing over the sacro-iliac articulation, and a band connected at its ends to said supporter proper at the upper sides 40 thereof and passing over the shoulders downward and along the median line and looped around said first mentioned band.

7. An abdominal support comprising a 50 supporter proper shaped to encase a pendulous abdomen, and a harness for carrying said supporter proper, said harness including a band secured to the lower border of said supporter proper at the inguinal region and encircling the innominate horizontally at a 55 point adjacent the anterior superior spines of the ilia and passing over the sacro-iliac articulation, and a band connected at its ends to said supporter proper at the upper 60 sides thereof and passing over the shoulders downward and along the median line and looped around said first mentioned band, and a third band connected at its ends to said second band adjacent its connection to said 65 supporter proper and running horizontally

from its place of attachment and crossing the median line at about the tenth dorsal.

8. An abdominal support comprising a 70 supporter proper shaped to encase a pendulous abdomen, and a harness for carrying said supporter proper, said harness including a band secured to the lower border of said supporter proper at the inguinal region and encircling the innominate horizontally at a point adjacent the anterior superior spines of the ilia and passing over the sacro-iliac articulation, and a band connected at its ends to said supporter proper at the upper 75 sides thereof and passing over the shoulders downward and along the median line and looped around said first mentioned band, a third band connected at its ends to said second band adjacent its connection to said supporter proper and running horizontally from its place of attachment and crossing 80 the median line at about the tenth dorsal, and a pad of suitable soft material secured to said second and third bands where they cross at the median line.

9. An abdominal support comprising a 85 supporter proper shaped to encase a pendulous abdomen, and a harness for carrying said supporter proper, said harness including a band secured to the lower border of said supporter proper at the inguinal region and encircling the innominate horizontally at a point adjacent the anterior superior spines of the ilia and passing over the sacro-iliac articulation, and a band connected at its 90 ends to said supporter proper at the upper sides thereof and passing over the shoulders downward and along the median line and looped around said first mentioned band, a third band connected at its ends to said second band adjacent its connection to said supporter proper and running horizontally from its place of attachment and crossing 95 the median line at about the tenth dorsal, and a pad of suitable soft material secured to said second and third bands where they cross at the median line, and means to adjust the lengths of said bands in fitting the supporter to the wearer.
